Primary Examiner — T Chase Nelson*Assistant Examiner* — Kelly L Gross(74) *Attorney, Agent, or Firm* — Sughrue Mion, PLLC(57) **CLAIM**

The ornamental design for a cooling device for neck, as shown and described.

DESCRIPTION

FIG. 1 is a first perspective view of the front, top and right side view of a cooling device for neck showing my new design;

FIG. 2 is a second perspective view of the rear, bottom and left side view thereof;

FIG. 3 is a front view thereof;

FIG. 4 is a rear view thereof;

FIG. 5 is a left side view thereof, a right side view being a mirror image;

FIG. 6 is a top view thereof;

FIG. 7 is a bottom view thereof; and,

FIG. 8 is a perspective view of usage showing a wearing state thereof.

The broken lines shown are included for the purpose of illustrating environmental structure and portions of the cooling device that form no part of the claimed design.
